ATTORNEY

UNITED STATES PATENT OFFICE.

CLIFFORD W. MARSH, OF BRIDGEPORT, CONNECTICUT.

GLUING MACHINE.

Application filed August 23, 1920. Serial No. 405,350.

To all whom it may concern:

Be it known that I, CLIFFORD W. MARSH, a citizen of the United States, residing at Bridgeport, county of Fairfield, State of Connecticut, have invented an Improvement 5 in Gluing Machines, of which the following is a specification.

This invention has for its object to produce a gluing machine by means of which 10 glue, or similar adhesive material, may be applied to a sheet of paper or the like without the necessity of spreading the glue on the sheet as is now common practice, the machine of the invention being provided 15 with mechanism whereby globules of glue may be deposited on the sheet at desired spaced apart points.

With the above and other objects in view, the invention comprises the construction, 20 arrangement and combination of parts as now to be fully described and hereinafter specifically claimed.

In the accompanying drawing forming a part of this specification,

25 Fig. 1, is a top plan view of the gluing machine with the cover partially broken away to better show the construction of the various parts;

Fig. 2, an end elevation looking from the 30 right in Fig. 1, showing the cover in section;

Fig. 3 an end elevation corresponding with Fig. 2, but with the cover removed, and showing a sheet of paper or the like 35 as when inserted in the machine, the movable parts being in a position different from that disclosed in Fig. 2;

Fig. 4 a section on line 4—4 in Fig. 1, showing a sheet as when inserted and 40 closing the glue depositing comb as when being elevated to deposit glue on the sheet; and

Fig. 5 is a section on line 5—5 in Fig. 1, showing the sliding frame resting in the 45 bottom of the glue pot.

10 denotes the base of the machine and 11 represents handles thereon by means of which the machine may be moved from place to place. A glue pot 12 of any desired configuration is adapted to rest on the base, lugs 13 being provided to locate the glue pot. Guide rods 14, imbedded in the base as indicated at 15, are for the purpose of supporting a sliding frame 16 adapted

to lie in the bottom of the glue pot. The 55 sliding frame preferably consists of a strip of metal bent upwardly at right angles at the two points indicated 17, outwardly at right angles at the two points indicated 18, then downwardly at right angles at the two 60 points indicated 19, and then inwardly at right angles at the two points indicated 20. The outwardly bent portions of the sliding frame, denoted by 21, and the inwardly bent portions, denoted by 22, are provided 65 with perforations, denoted by 23 and 24, respectively, adapted to slidably receive the guide rods. The sliding frame is thus located in upright position on the guide rods as will be understood. Adjacent its opposite ends the base is provided with lugs 25 which are perforated to rotatably receive a pivot rod 26 to the opposite ends of which are rigidly secured, as indicated at 27, hand levers 28, the hand levers, as shown, being 70 preferably located on the outer sides of the lugs. The front ends of the hand levers are provided with finger pieces 29 and the rear ends are provided with hooks 30 adapted 75 to engage lifting pins 31 carried by the sliding frame. Secured to the portion of the sliding frame which is adapted to lie in the bottom of the glue pot is a glue depositing comb 32 provided with teeth 33.

The base of the machine also carries 80 upright posts 34, two located adjacent each end of the base and preferably at opposite sides of the guide rods, and each provided with shoulders 35. A plate 36 provided with perforations 37 is adapted to rest on shoulders 90 35, and a stop plate 45 is adapted to rest on the perforated plate. In this embodiment of my invention the glue transferring portions 33 of the comb are limited in their upward movement, being designed to stop 95 short of the under surface of the upper work supporting plate, to prevent the comb from depositing glue on the plate itself, if the machine should be operated without the work being in place, which would cause glue 100 to be smeared on the top side of the work when next inserted in the machine. It is for this purpose that I provide the upper work supporting plate with the perforations 37 into which the portions 33 may enter, 105 should the machine be operated at a time when there was no work in the machine, thus preventing the application of glue to

the upper plate, and still providing a glue applying instrumentality that is insured of touching the work when in place in the machine. The stop plate has struck from it 5 downwardly extending stops 46 adapted to limit the inward movement of the sheet to be glued when placed in the machine, as will be made clear, the stops passing downwardly through certain of the perforations 10 of the perforated plate. Both the stop plate and perforated plate are cut away as indicated at 38 to allow the sliding frame to pass when it is caused to be elevated by manipulation of either of the hand levers, 15 and both of said plates are provided with openings through which the upright posts freely pass. A glue guard 39, preferably shaped as more clearly shown in Figs. 2, 3, and 4, has its front edge resting in lugs 20 40 on the base and its rear edge resting upon the rear edge of the glue pot. The glue guard is slotted as indicated at 41, the slots being in alinement with the teeth of the glue depositing comb and with the perforations in the perforated plate. 42 denotes a guide plate for the sheet, denoted by A, or other material to be glued, and 43 denotes a cover for the machine when not in use, the lower edge of the cover being 30 capable of resting in a depression 44 in the machine base. The glue pot may be filled to any desirable depth with glue B.

It will be noticed that most of the parts of the machine invented by me are easily 35 removable from the base and from each other. After the base has had secured to it the guide rods, the upright posts and the hand levers, the glue pot may be placed in position on the base, and supplied with 40 glue. The sliding frame may then be positioned on the guide rods in the bottom of the glue pot, the glue guard may then be laid over the pot, the perforated plate may then be placed on the upright posts and the stop 45 plate afterwards placed on said posts and against said perforated plate. The machine is then ready for use. To disassemble the parts, the operations are reversed.

To use the machine, a sheet is inserted 50 from the front, as shown very clearly in Figs. 3 and 4 between the glue guard and the perforated plate, the stops limiting the inward movement of the sheet. The right hand end of the sheet may be properly positioned by means of the guide plate shown 55 more clearly at the right in Fig. 1. When now the finger piece of the hand lever is pushed down, the sliding frame causes the depositing comb and its teeth to move upwardly. It will be apparent that the upward movement of the sliding frame will be 60 limited by engagement of the hooks at the rear end of the hand levers with the lifting pins, said hooks being in the position shown 65 in Fig. 2, when the sliding frame is in the

bottom of the glue pot, and in the position shown in Fig. 3, when the sliding frame is elevated. As the comb teeth are elevated from the glue, each will carry a small ball or globule of glue. When now the teeth 70 move into contact with the sheet, the glue will be deposited on the sheet as will be obvious. The comb is adapted to pass but a slight distance into the perforations in the perforated plate, so that the sheet will not 75 be broken as the glue is being applied, and the perforated plate and stop plate, by reason of their free engagement with the upright posts, are adapted to slide up on said posts should a sheet of any considerable thickness 80 be placed in the machine, the machine being thus capable of gluing sheets of any thickness. The glue guard is cut away and shaped as shown so that the glue deposited 85 will not be smeared when the sheet is removed from the machine.

As soon as the finger piece is released, the sliding frame and comb will move downwardly in the glue and the sheet may then be withdrawn.

What I claim is,

1. In a gluing machine, a glue pot, a sliding frame therein, a glue depositing comb provided with teeth carried by said sliding frame, and means for causing said teeth to be moved upwardly in said glue pot, said means comprising a hand lever adapted to have a sliding engagement with said sliding frame and provided with a stop for limiting the upward movement thereof. 90

2. A gluing machine comprising a base, a glue pot carried thereby, guide rods carried by said base, a sliding frame arranged in said glue pot and adapted to reciprocate on said guide rods, a glue depositing comb carried by said sliding frame, and means for actuating said sliding frame, said actuating means comprising hand levers pivotally supported by said base and provided with hooks adapted to engage lifting pins carried by said sliding frame, said hooks limiting the upward movement of said sliding frame. 105

3. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, means for actuating said sliding frame to cause said teeth to be elevated, upright posts carried by said base, a perforated plate and a stop plate freely carried by said posts, said stop plate arranged above said perforated plate and provided with stops depending through said perforated plate and a glue guard arranged over said glue pot and beneath said perforated plate, whereby a sheet to be glued may be positioned on said glue guard and beneath said perforated 120 125 130

plate so as to receive globules of glue from said teeth.

4. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, means for actuating said sliding frame to cause said teeth to be elevated, upright posts carried by said base, a perforated plate and a stop plate freely carried by said posts, said stop plate resting on said perforated plate and having stops which pass downwardly through certain of the perforations in said perforated plate, and a glue guard arranged over said glue pot and beneath said perforated plate and provided with slots, said perforations, slots and teeth being in alinement with each other for the purpose specified.

5. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, means for actuating said sliding frame to cause said teeth to be elevated, upright posts carried by said base, a perforated plate and a stop plate freely carried by said posts, said stop plate resting on said perforated plate and having stops which pass downwardly through certain of the perforations in said perforated plate and both of said plates being cut away to allow passage of said sliding frame, and a slotted glue guard arranged over said glue pot and beneath said perforated plate, whereby a sheet to be glued can be inserted in said machine between said glue guard and perforated plate and against said stops, and said sliding frame can be elevated to cause said teeth to deposit globules of glue on said sheet.

45 6. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, levers for actuating said sliding frame to cause said teeth to be elevated and means carried by said levers to limit the upward movement of said sliding frame, in combination with upright posts carried by said base, a perforated plate and a stop plate carried by said posts, said stop plate resting on said perforated plate and provided with stops which pass downwardly through certain of the perforations in said perforated plate, and certain other of said perforations adapted to be entered by said teeth, and a slotted glue guard arranged over said glue pot and beneath said perforated plate.

7. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, levers for actuating said sliding frame to cause said teeth to be elevated, a pivot rod carried by said base and to which said levers are rigidly secured, whereby when one of said levers is actuated the other will also be actuated, hooks carried by said levers to limit the upward movement of said sliding frame, upright posts carried by said base, a perforated plate and a stop plate freely carried by said posts, said stop plate resting on said perforated plate and provided with stops which pass downwardly through certain of the perforations in said perforated plate, and certain other of said perforations adapted to be entered by said teeth, and a glue guard arranged over said glue pot and beneath said perforated plate, said glue guard provided with slots in alinement with said perforations and teeth.

8. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, means for actuating said sliding frame to cause said teeth to be elevated, upright posts carried by said base, a perforated plate freely carried by said posts, stops extending downwardly below said perforated plate, and a glue guard arranged over said glue pot and beneath said perforated plate and provided with slots, the perforations in said perforated plate, the slots in said glue guard, and the teeth of said comb being in alinement with each other, for the purpose specified.

9. A gluing machine comprising a base, a glue pot located thereon, guide rods carried by said base, a sliding frame arranged in said glue pot and adapted to reciprocate on said guide rods, a glue depositing comb carried by said sliding frame and provided with teeth, levers whereby said teeth may be elevated, each of said levers provided with hooks to limit the upward movement of said teeth, upright posts carried by said base, a perforated plate freely carried by said posts and adapted for upward movement thereon, stops extending downwardly below said perforated plate and adapted for upward movement with said perforated plate, and a slotted glue guard arranged over said glue pot and beneath said perforated plate and stops.

10. A gluing machine comprising a base, a glue pot supported thereby, a sliding frame having a plurality of glue depositing teeth normally immersed in said glue pot,

a lever for actuating said frame, and a stop on said lever cooperating with said frame for limiting its upward movement.

11. A gluing machine comprising a base, a glue pot mounted thereon, a frame carrying glue depositing teeth, said frame reciprocating in said glue pot, an upper mate-

rial support, and a lower material support, said supports adapted to receive the material to be glued between them said lower support 10 being provided with openings for the passage of said teeth.

In testimony whereof I affix my signature,
CLIFFORD W. MARSH.
